UNITED STATES PATENT OFFICE.

HERBERT E. SHREEVE, OF MILBURN, NEW JERSEY, ASSIGNOR TO WESTERN ELECTRIC COMPANY, OF NEW YORK, N. Y., A CORPORATION OF ILLINOIS.

TELEPHONE-TRANSMITTER.

1,077,373.

Specification of Letters Patent.

Patented Nov. 4, 1913.

Application filed October 13, 1911. Serial No. 654,485.

To all whom it may concern:

Be it known that I, HERBERT E. SHREEVE, subject of the King of England, residing at Milburn, in the county of Essex and State 5 of New Jersey, have invented a certain new and useful Improvement in Telephone-Transmitters, of which the following is a full, clear, concise, and exact description.

This invention relates to loud speaking 10 transmitters of the differential type, and more particularly to the production of a loud speaking transmitter in which the deleterious effect of using the comparatively heavy current necessary for its operation is 15 avoided.

One of the objects of this invention is to produce a loud speaking transmitter which will operate on heavy current and in which the usual casing and bell are dispensed with, 20 the parts being made massive and provided with a large area of cooling surface, all parts being open to permit a free circulation of air for cooling purposes.

Another object of this invention is to provide means for the equalization of the gaseous pressure on the two sides of the movable electrode and for the relief of gas pressures inside the granule chamber; also to provide for the free expansion of the movable electrode in the direction of its diameter and of the electrode stem in the direction of its 25 length.

Another object is the provision of a gland 30 of peculiar design through which the electrode stem passes, whereby the use of textile fabrics is obviated and satisfactory mechanical adjustment provided.

Another object of this invention is the use 35 of catlinite in the construction of the walls of the electrode chamber.

In the drawings—Figure 1 is a detail perspective view of the improved transmitter, partly in section; Fig. 2 is a sectional elevation. Fig. 3 is a diagram of the circuits.

40 There is shown a transmitter having a massive back plate or support 10 with a rearwardly extending portion 11 on which are formed flanges 12 for the purpose of dissipating heat. Attached to the rearward 45 end of the part 11 is a lug 13 for attachment to the standard 14 of the ordinary desk stand. Mounted on the front of the support 10 is a heat-dissipating plate 15, attached to the support 10 by means of screws 50 55 16 and separated therefrom by a plurality of

washers 17. On the forward face of the support 10 is an annular groove 18 defining an electrode support 19 to which is attached by soldering or otherwise a platinum electrode 55.

Attached to the support 10, by means of a plurality of screws 20, insulated from the support by the insulating bushings 21, but spaced apart therefrom by spacing bolts 22 and washers 23, is the front plate or support 24. On the rear face of this support 24 is an annular groove 25 defining an electrode support 26 to which is attached the platinum electrode 56. This groove 25 is opposite the groove 18, and mounted in these two grooves 70 is a catlinite bushing 27. The two electrodes, together with the catlinite bushing, define an electrode chamber. Formed on the front face of the support 24 are a plurality of circumferential heat-dissipating 75 flanges 28. The support 24 is provided with a hole 29 which, at its outer end, is countersunk as at 30 to form a stuffing box. Attached to the front face of the plate 24 is a face plate 31 having the usual form of 80 mouthpiece 32 attached to the front thereof. This face plate 31 is attached to the front plate or support 24 by means of the screws 33. The rear face of the face plate 31 is recessed to form a support for an insulating washer 34 against which abuts a diaphragm 35.

Mounted on the front face of the support 24 is a spring member 36 fastened to the support by the screws 37. The outer end of this 90 spring 36 contacts with the insulating washer 43 on the diaphragm 35, and constitutes a damping spring for the diaphragm.

Mounted in the electrode chamber is a 95 movable or plunger electrode 38. This electrode 38 is provided with a stem passing through the hole 30 in the support 24 and through a perforation in the diaphragm 35. The outer end of this stem is threaded as at 100 39, and provided with a thumbnut 40. Mounted on the stem is an insulating bushing 41 of catlinite. A mica washer 42 is mounted in the stuffing box 30, and located between this washer 42 and the insulating 105 washer 43, mounted on the rear face of the diaphragm, is a spring 44 which maintains the washers 42 and 43 in place, permits the diaphragm to vibrate in response to the voice currents and compensates for change 110

in distance between the diaphragm 35 and the electrode 38. The electrode chamber is partly filled with carbon granules 45.

The structure of the granular chamber, 5 described above, is one that permits the equalization of gas pressure of the two sides of the movable electrode 38, owing to the movable electrode being of smaller diameter than the inside diameter of the catlinite 10 bushing 27. The catlinite bushing 27 fitting loosely in the annular grooves on the front and back plates allows any excess of gas to escape from the chamber without at the same time permitting the escape of carbon granules. The movable electrode 38 has sufficient 15 room within the catlinite bushing 38 to allow it to expand in the direction of its diameter, and the stem 39 attached thereto may expand in the direction of its length, any increase in length due to heating being compensated for by means of the spring 44.

Mounted on the rear face of the support 10 is a plate 46 formed of insulating material. A conducting block 47 is fastened 20 thereto, and a conductor 48 leads therefrom and makes contact with the diaphragm and thus with the movable electrode 38, as clearly shown in Fig. 1. Insulating bushings 50 are provided to insulate the conductor 48 from the back support 10 and the front support 24. A binding post 51 is mounted on the plate 46 and makes contact with the front plate 24 at 52. This binding post 51 passes through a hole 53 in the 25 back plate 10, and is insulated therefrom by the insulating washer 54.

In Fig. 3, which shows a diagram of the circuits, the electrodes 55 and 56 are connected to the extremities of the primary 60 of the induction coil 61, by the wires 70 and 71, respectively, the secondary 62 being connected to the line. The movable electrode 38 is connected to the middle point of the primary 60 through the local battery 63. 45 The operation is as follows:—The normal current flow is in opposite directions through the primary, the core remaining neutral. One oscillation of the diaphragm 35 and its associated electrode 38 causes current to rise in one half of the primary 60 and simultaneously to fall in the other half, and, as these effects are opposite the resultant action on the secondary produces a 50 strong rise in one direction through the whole length of the secondary equal to the sum of the individual effects. On the reverse oscillation the current in the secondary first falls to zero and then reverses to an equal degree.

60 The construction herein shown is such that a transmitter of this type will operate efficiently under comparatively heavy current without undue heating. The construction is open, no casing being provided. All 65 metal parts are made heavy and provided

with ample means for dissipating any heat that may be generated. The use of catlinite as insulation and as the material for the walls of the granule chamber insures durability of the transmitter under the severest 70 service conditions.

I claim:

1. In a telephone transmitter, the combination of two stationary electrodes spaced apart, heat-dissipating projections integral therewith, an insulating bushing located between and concentrically mounted with respect thereto and defining a chamber, carbon granules therein, a plunger electrode of less diameter than the inside diameter of the 80 bushing, mounted in said chamber, whereby the plunger electrode may have room to expand in the direction of its diameter, a stuffing box in one of the stationary electrodes, a diaphragm, a stem integral with 85 the plunger electrode, passing through the stuffing box and adjustably connected with the diaphragm, a mica washer mounted in the stuffing box and surrounding the electrode stem, and a spring mounted between 90 the diaphragm and the mica washer, whereby the washer is held in the stuffing box and the escape of carbon granules from the chamber is prevented.

2. In a telephone transmitter, the combination of two stationary electrode supports spaced apart, heat-dissipating flanges integral therewith, electrodes mounted on adjacent faces thereof, an annular catlinite bushing located between the electrode supports 100 and forming therewith an electrode chamber, a movable electrode mounted in said chamber, a diaphragm, and means mechanically connecting said diaphragm with said movable electrode, said connecting means 105 passing through an orifice in one of the stationary electrode supports, and granular carbon in said chamber and on either side of said movable electrode.

3. In a telephone transmitter, the combination of a rigid electrode forming the back of the carbon chamber, a perforated electrode spaced therefrom and forming the front wall of the carbon chamber, two annular grooves, one in each electrode, and a 115 bushing fitting into said annular grooves.

4. In a telephone transmitter, the combination of massive front and back plates spaced apart and provided with heat-dissipating flanges, annular grooves in the opposing faces of said back plates defining electrode supports, electrodes mounted thereon, a heat-resisting bushing loosely mounted in said annular grooves and forming with said back plates an electrode chamber, a movable electrode mounted in said chamber out of contact with either wall thereof, a diaphragm, connecting means passing through an orifice in one of said back plates and connecting said movable 125 130

electrode and said diaphragm together, whereby the vibrations of said diaphragm are communicated to said electrode, granular carbon in said chamber on either side of said movable electrode, and means to prevent the escape of the carbon granules through the orifice in the front plate.

5. In a telephone transmitter, the combination of two rigid electrodes, massive 10 supports therefor spaced apart and provided with heat-dissipating projections, a catlinite bushing located between said supports and forming therewith an electrode chamber, a diaphragm, a movable electrode 15 located in said chamber and of less diameter than the inside diameter of the bushing, means for connecting said electrode and diaphragm together, said means comprising a stem rigidly attached to the electrode and 20 passing through one of the supports and through the diaphragm, resilient compensating means located between the diaphragm and one of the supports, and means on the end of the stem whereby the distance between the diaphragm and the movable electrode may be adjusted.

6. In a telephone transmitter, the combination with a stationary back plate, an electrode mounted on the front face thereof, an 30 annular groove in said back plate and surrounding the electrode, heat-dissipating flanges formed on the rear face of the back plate, a stationary front plate spaced apart from but connected to the back plate, heat- 35 dissipating flanges formed on the front face

thereof, an electrode mounted on the back face thereof, an annular groove in the front plate and surrounding the electrode, a catlinite bushing fitting into said groove and surrounding said electrode and forming 40 therewith a closed chamber, a movable electrode in said chamber, a diaphragm, a stem mechanically connecting the diaphragm and the movable electrode, said stem passing through a perforation in the stationary 45 front plate, a gland in the front face of the front plate, and a mica washer in said gland and surrounding said stem, thereby preventing the escape of carbon granules from said chamber while permitting the 50 escape of gas.

7. In a telephone transmitter, the combination of a diaphragm having a central perforation, two rigid electrodes, one having a central perforation, a movable electrode 55 between said rigid electrodes, an expandable stem passing through the perforations in said diaphragm and said perforated rigid electrode, one end operatively connected with the diaphragm, the other end attached 60 to the movable electrode, and means for compensating for the expansion of said stem.

In witness whereof, I, hereunto subscribe my name this 12th day of October A. D., 65 1911.

HERBERT E. SHREEVE.
